Primary Examiner — Katrina A Betton(74) *Attorney, Agent, or Firm* — Foley & Lardner LLP(57) **CLAIM**

The ornamental design for an automotive side view mirror, as shown and described.

DESCRIPTION

FIG. 1 is a perspective view of a rear view mirror shown on the left side of a vehicle in broken lines, the right side is a mirror image of that shown;

FIG. 2 is an elevational side view;

FIG. 3 is an elevational top view;

FIG. 4 is an elevational rear view; and,

FIG. 5 is an elevational front view thereof.

The vehicle shown in broken lines is for illustrative purposes only and forms no part of the claimed design.
